US0D1085428S

(12) **United States Design Patent** (10) **Patent No.:** **US D1,085,428 S**
(45) **Date of Patent:** **** Jul. 22, 2025**

(54) **BACK BANDAGE**

(71) Applicant: **Bauerfeind AG**, Zeulenroda-Triebes (DE)

(72) Inventor: **Hermann Rokitta**, Mülheim an der Ruhr (DE)

(73) Assignee: **BAUERFEIND AG**, Zeulenroda-Triebes (DE)

(**) Term: **15 Years**

(21) Appl. No.: **29/913,204**

(22) Filed: **Sep. 28, 2023**

Related U.S. Application Data

(62) Division of application No. 35/513,912, filed on Sep. 29, 2021 (U.S. filing date under 35 U.S.C. 384), and having an international filing date of Sep. 29, 2021, now Pat. No. Des. 1,006,237.
